UNITED STATES PATENT OFFICE

2,396,682

PRODUCTION OF ALKYL AROMATICS

Don R. Carmody, Hammond, Ind., assignor to
 Standard Oil Company, Chicago, Ill., a corpora-
 tion of Indiana

Application August 31, 1942, Serial No. 456,769

6 Claims. (Cl. 260—671)

This invention relates to the production of alkyl aromatic hydrocarbons and relates more particularly to the production of ethylbenzene by the alkylation of benzene with ethylene from a dilute ethylene stream.

Monoalkylbenzenes and particularly the lower boiling monoalkylbenzenes such as ethylbenzene or isopropylbenzene have been found to be valuable constituents in aviation fuels because of their very high octane number particularly under "supercharged" conditions. The amount present in ordinary refinery streams of petroleum hydrocarbons is comparatively negligible and even in the products from such processes as catalytic or thermal cracking, catalytic aromatization, etc., the ultimate yield of low boiling monoalkyl aromatics is comparatively low. It has been known for some time that these alkylbenzenes can be synthesized by the alkylation of aromatic hydrocarbons with olefins in the presence of activating catalysts, etc. It is generally desirable that the olefin stream be rich in olefins not only because of the great reduction in reaction space thus obtained but also because the yield based on olefins fed to the process is much higher when diluting inert gases are substantially eliminated.

It is an object of this invention to provide an improved process for the alkylation of aromatic hydrocarbons with olefinic gases from an olefin stream containing inert gases. Another object of my invention is to provide an improved process for the production of alkyl aromatic hydrocarbons from dilute olefin-containing gases without elaborate fractionation equipment. A still further object of my invention is to provide an improved process wherein hydrocarbons valuable for aviation fuels are prepared from refinery fuel gases and a benzene-rich fraction. Further objects and advantages will become apparent as the description of my invention proceeds.

The accompanying drawing illustrates apparatus suitable for carrying out one preferred embodiment of my invention and is in the form of a simplified flow diagram.

Briefly stated my invention contemplates the absorption of ethylene from a refinery fuel gas stream in polyalkyl aromatic hydrocarbons and the alkylation of benzene with the absorbed ethylene without removal of the ethylene from the enriched absorption medium. A further embodiment of my invention contemplates subjecting the polyalkyl aromatic hydrocarbon fraction having low boiling olefinic gases absorbed therein to alkylation conditions to form additional polyalkyl aromatics of higher molecular weight and

the contact of the polyalkyl aromatic alkylate thus formed with benzene in the presence of a catalyst to form monoalkyl aromatic hydrocarbons.

5 Referring now to the drawing, a dilute olefin stream enters absorber 10 via line 11 from a suitable source (not shown). A particularly suitable olefin feed for my process is a refinery fuel gas stream or dilute ethylene stream containing 10 not only ethylene but hydrogen, methane, ethane and possibly traces of propane and propylene. The ethylene content of this stream can vary from about 3% by volume to about 20% by volume or higher and such gaseous feed streams are 15 to be found in large quantities in any commercial petroleum refinery being employed therein suitably as fuel gases, etc. Any ethylene-containing stream can be used, however, such as those from gas cracking or catalytic dehydrogenation and the exact source is not critical. In absorber 10 the olefin-containing stream is contacted with a polyalkyl aromatic hydrocarbon stock from line 12. This can suitably be a hydrocarbon stock higher boiling than is generally 20 considered suitable or desirable in gasoline streams and may contain such mixtures as diethylbenzene, ethyltoluene, triethylbenzene, propyltoluene, etc. The absorber is maintained at a pressure within the approximate range of about 30 atmospheric to about 500 pounds per square inch and at temperatures within the approximate range of 50 to 150° F. The unabsorbed gases, substantially olefin-free, pass overhead through line 13 while the enriched polyalkylbenzenes are 35 withdrawn from absorber 10 through line 14 and directed via line 15 and 15a and valve 16 to mixer 17 where they are thoroughly mixed with benzene from line 18 in such proportions that the mol ratio of available olefin to benzene is not greater than about 1 to 1 and preferably is of the order 40 of about 0.4 to 1 to 0.6 to 1.

The mixture of benzene and absorbate passes 45 from mixer 17 via line 19 to alkylator 20. Alkylator 20 can be any conventional reactor for contacting hydrocarbons and catalyst, and suitably can be a tower containing a pool of catalyst. It can be equipped with stirring devices or other means such as jet injectors or turbomixers for insuring adequate contact of the various streams. 50 Fresh catalyst can be added to alkylator 20 via lines 21 and 22 and may comprise any of the conventional alkylation catalysts such as the metal halides or their complexes, sulfuric acid, hydrogen fluoride, etc. A particularly suitable catalyst is an aluminum chloride hydrocarbon

complex having a heat of hydrolysis within the approximate range of 60 to 75 large calories per gram of active aluminum, as described in co-pending application Serial No. 311,950, now U. S. Patent 2,308,560. With this catalyst, alkylator 20 is operated at temperatures within the approximate range of 100° F. to 300° F., preferably at about 120 to 200° F., and at atmospheric to 1000 pounds per square inch pressure, preferably at pressures within the approximate range of 100 to 300 pounds per square inch.

An activator can be added through line 23 to mixer 17, or can be absorbed in either of the incoming hydrocarbon streams if desired. It can also be added directly to alkylator 20. The activator suitably can be a hydrogen halide such as HCl, HBr, or a substance yielding a hydrogen halide under the reaction conditions, as, for example, alkyl halides, chlorine, moisture, etc. It can be present in amounts ranging from about 0.1% to 10%, based on the catalyst, preferably about 4%.

From alkylator 20 the reaction mixture passes to settler 24 via line 25 in which separation of the catalyst from the hydrocarbons is accomplished, the catalyst being withdrawn through line 26 and if still active for promoting alkylation is recycled via line 27 to line 22 and alkylator 20. If the catalyst is substantially spent, it can be withdrawn via line 28. By the proper adjustment of valves 29 and 30 in lines 21 and 28 respectively, a part of the catalyst can be continuously withdrawn for regeneration and the remainder recycled with fresh catalyst to alkylator 20.

The hydrocarbons are withdrawn from settler 24 via line 31 and will comprise the monoalkylbenzene hydrocarbons formed by the alkylation of the benzene with the dissolved olefins, any unreacted dissolved olefins and the polyalkylbenzenes employed as the absorption medium. In addition, a certain amount of the polyalkylbenzenes will undergo dealkylation, the separated alkyl groups also serving to alkylate the benzene present. These are desirably directed to a flash drum 32 operating at atmospheric pressure or slightly above and at temperatures within the range of about 80° to 200° F. The gases are flashed off together with some benzene and pass overhead through line 33 to scrubber 34. The gases and benzene are recovered by scrubbing with higher boiling alkylbenzenes from fractionator 35 which enter scrubber 34 via line 36. If desired the polyalkylbenzenes from an outside source which may be identical with that for absorber 10 can be substituted, the scrubbing medium entering through line 37 which joins line 36.

The liquid hydrocarbons from flash drum 32 are withdrawn via line 38, scrubbed in caustic scrubber 39 to remove any catalyst present as well as any hydrogen chloride activator dissolved therein, the dilute caustic entering caustic scrubber 39 from line 40 being withdrawn through line 41. The scrubbed hydrocarbons pass from caustic scrubber 39 to fractionator 35 via line 42. Fractionator 35 can be any conventional fractionating system which will serve to separate the liquid hydrocarbons into a benzene fraction, a monoalkylbenzene fraction containing primarily ethylbenzene and a polyalkylbenzene fraction. The separated benzene passes overhead and while it may be discarded via line 43, it is preferably recycled via line 44 to line 18 where it is mixed with incoming fresh benzene and directed to mixer 17. The polyalkylbenzenes are withdrawn

from the lower portion of fractionator 35 and recycled to absorber 10 via line 45. A portion of the polyalkylbenzenes may be by-passed to scrubber 34 by opening valve 46 in line 47 which joins line 36, the enriched polyalkylbenzene medium being withdrawn from scrubber 34 through line 48 which rejoins line 45 leading to absorber 10. The desired monoethylbenzene is withdrawn through line 49.

As an alternative method of operation, the absorbate from absorber 10 can be directed via line 14a to alkylator 50. In alkylator 50 the polyalkylbenzenes containing absorbed olefins are contacted with an alkylation catalyst such as aluminum chloride, a hydrocarbon complex containing aluminum chloride, sulfuric acid, hydrogen fluoride, etc. For example, if an aluminum chloride hydrocarbon complex is employed the reaction in alkylator 50 can be carried out at temperatures within the approximate range of 50° to 250° F. and under superatmospheric pressures. The catalyst can be added through line 51 and can be either fresh catalyst from line 52 or recycle catalyst from line 53. An activator, which can be a hydrogen halide such as HCl or HBr or a substance affording a hydrogen halide under the reaction conditions can be added through line 54. The product and catalyst pass from alkylator 50 through line 55 to settler 56 wherein a separation is made between the catalyst and the hydrocarbons, the catalyst being withdrawn through line 57 and either discarded through line 58 or recycled through line 59 which joins line 53. As before, a part of the catalyst from settler 56 can be discarded and the remainder recycled with additional catalyst by the proper adjustment of valves 60 and 61 in lines 58 and 59 respectively. The product layer is withdrawn through line 62 to line 15a and mixed with benzene from line 18 in mixer 17 and directed to alkylator 20 as previously discussed. In the event that the process is carried out in this manner, the reaction in alkylator 20 is essentially one of dealkylation of the polyalkylbenzene in the presence of excess benzene which in turn is alkylated primarily to monoalkylbenzene. Higher temperatures such as those within the range from about 100° to 300° F. are suitable and the catalyst employed therein should be at least as active as that used in alkylator 50 and preferably of greater activity. The mol ratio of benzene to polyalkylbenzenes introduced into alkylator 20 should be at least 1 to 1 and preferably greater than the number of mols of olefin attached to the polyalkylbenzene as the alkyl group. The products from alkylator 20 are treated in substantially the same manner as previously described except that it will not be necessary to employ the flash drum scrubber, the products going directly to the caustic washer 39 and fractionator 35 with the appropriate recycle therein described. Alternately, the products can be fractionated to yield a benzene fraction, a monoethylbenzene fraction, a light polyalkylbenzene fraction and a heavy polyalkylbenzene fraction. The heavy polyalkylbenzene fraction is returned to absorber 10 via line 45, while the light polyalkylbenzene fraction is withdrawn through line 64, and although it can be discarded through line 65, it is preferably directed to alkylator 50 via lines 66 and 14a. In this manner of operation, only the heaviest polyalkylbenzenes are employed as an absorbing medium, and loss of light products by the sweeping effect of the entering gases is substantially eliminated. The lighter

polyalkylbenzenes are added to the alkylator, however, so that they can also be converted to higher boiling polyalkylbenzenes by ethylene as hereinbefore described. A particularly advantageous method of operation is to introduce fresh catalyst into alkylator 20 via line 21, and direct the used catalyst from settler 24 into alkylator 50 via lines 26, 27, 63, 53 and 51. In this manner, the most active catalyst is employed for the dealkylation-alkylation reaction which requires a higher degree of activity than the alkylbenzene-olefin alkylation reaction.

The use of polyalkylbenzenes as an absorbing liquid to concentrate olefins has many advantages. Because of the high boiling range of the hydrocarbons, they are not volatile enough to cause losses by the sweeping effect of the dilute olefin stream. They differ sufficiently from ethylbenzene in distillation range so that recovery by fractionation is carried out without difficulty. In addition the polyalkylbenzenes not only do not interfere with the alkylation of the benzene by the absorbed olefins but even appear to act as an aid by suppressing the formation of di- and tri-alkylbenzenes. An added advantage of the use of an absorbing liquid of this type is in the formation of additional amounts of monoalkyl aromatics by the dealkylation of the polyalkylbenzene and the alkylation of the benzene by the alkyl radical thus produced.

Although I have described my process with special reference to one embodiment thereof, it should be noted that this is by way of illustration and not by way of limitation, and that I intend to be limited only to the extent set forth in the appended claims. Moreover, various details have been omitted from the drawing and the description thereof for the sake of simplicity and clarity, and these details, such as pumps, heat exchangers, automatic control devices, etc. will be readily supplemented by one skilled in the art wishing to practice my invention.

I claim:

1. A process for the production of monoalkylaromatic hydrocarbons comprising subjecting an aromatic hydrocarbon to alkylation with at least one polyalkylaromatic hydrocarbon in the presence of an alkylation catalyst under alkylation

conditions adapted to yield both mono- and polyalkylaromatic hydrocarbons, separating monoalkylaromatic hydrocarbons from the alkylation product, recovering relatively high boiling and relatively low boiling fractions of the higher alkylated aromatic hydrocarbons, absorbing olefins in one of said fractions, subjecting both of said fractions and said absorbed olefins to alkylation in the presence of an alkylation catalyst under conditions to yield predominantly polyalkylaromatic hydrocarbons, and supplying said polyalkylaromatic hydrocarbons to the first-mentioned alkylation.

2. A process for the net production of predominately monoalkylbenzene which comprises contacting an olefin-containing gas with a liquid hydrocarbon mixture consisting essentially of polyalkylbenzenes produced in the system, absorbing olefins from said gas in said polyalkylbenzenes, contacting said absorbed olefin and said polyalkylbenzenes in the presence of an alkylation catalyst under alkylation conditions, recovering a total alkylate predominating in polyalkylbenzenes, adding benzene to the total alkylate, contacting the polyalkylbenzene and benzene mixture with a second quantity of a similar alkylation catalyst at a higher temperature than employed in the first alkylation, recovering from the second alkylation an alkylate containing substantial amounts of monoalkylbenzene together with a smaller proportion of polyalkylbenzene than in the total alkylate, separating the residual polyalkylbenzene and the desired monoalkylbenzene in the second alkylate, and recycling the polyalkylbenzene to the first alkylation step.

3. A process according to claim 2 in which the olefin-containing gas comprises dilute olefin stream.

4. A process according to claim 2 in which said olefin-containing gas is a dilute ethylene stream.

5. A process according to claim 2 in which said olefin-containing gas is a refinery fuel gas.

6. A process according to claim 2 in which said alkylation catalyst is selected from the group consisting of metal halides and metal halide-hydrocarbon complexes.

DON R. CARMODY.
